UNITED STATES PATENT OFFICE.

HARRY STIBBS, OF NORWOOD, OHIO.

RAIL-CLAMP.

932,186.

Specification of Letters Patent. Patented Aug. 24, 1909.

Application filed December 26, 1908. Serial No. 469,455.

To all whom it may concern:

Be it known that I, HARRY STIBBS, a citizen of the United States, residing at Norwood, in the county of Hamilton and State of Ohio, have invented certain new and useful Improvements in Rail-Clamps, of which the following is a specification.

My invention relates to improvements in clamping mechanism to lock car trucks in position on their rails. One of its objects is to provide a simple and efficient mechanism by means of which the trucks of steam shovels, traveling cranes, pile drivers, or the trucks of any car may be firmly locked in any desired position upon the rails.

Another object is to provide an improved clamping mechanism for such purpose, which is readily applied and detached, and is conveniently portable.

It further consists in certain details of form, combination and arrangement, all of which will be more fully set forth in the description of the accompanying drawings, in which:

Figure 1 is a side elevation of a flat car adapted to carry a steam shovel, crane, pile driver, engine or like mechanism, and showing the wheels or trucks locked in position upon the rails. Fig. 2 is a front elevation of one of my improved clamping mechanisms in position to be clamped upon a rail, which is shown in cross section. Fig. 3 is a side elevation of the same. Fig. 4 is a rear elevation of the same. Fig. 5 is a perspective view of one of the serrated shoes, detached. Fig. 6 is a perspective view of a detachable slack wedge employed in connection with my improved clamp. Fig. 7 is a side elevation of a modification.

In the accompanying drawings, A, represents the body of a car such as employed to support various mechanisms used in railway construction and repair, such as steam shovels, engines, cranes, and pile-drivers.

B, represents the car-trucks of ordinary construction, and b the wheels supported upon a pair of rails, E. It is desired to move such cars forward and backward from time to time and to lock them in position upon the rails while the mechanism carried by car, A, is in operation.

D, D', represent two jaws of the rail clamp, which are hinged together at d, so as to open centrally during the act of applying or detaching the clamp from the rail. The free ends, d', d'', of the jaws are adapted to

engage the under faces of the head, e, of the rail, E.

F, represents rearwardly projecting brackets carried by jaws, D, D', said brackets being armed with hardened and serrated shoes, G, which are preferably of a shape to be conveniently machined and each provided with a tongue, g, to enter corresponding recesses in the brackets, F. The forward ends of shoes, G, abut against shoulders, g', of the jaws, D, D', to take the thrust, and the shoes are held in place by screws, g'', passing through slotted openings in the shoes. Coiled springs, m, seated in recesses in the inner faces of jaws, D, D', serve to automatically open said jaws when handle, h', is in the raised position. A lever, H, is pivotally attached to jaws, D, D', by means of a pin, h, passing through ears, d², d³, formed integral with the jaws, D, D'. The lever, H, has a handle, h', at one end and cam-shaped hooks, h², h³, on opposite sides of jaws, D, D', at the opposite end. The jaws, D, D', can only be opened when the handle, h', is in the raised position, as shown in Figs. 1, 2 and 3, as in this position the cams, h², h³, are disengaged from the sides of jaws, D, D'. The extent to which the jaws, D, D', can be opened when handle, h', is raised, is limited by ears, d², d³, engaging the inner faces of cams, h², h³. When the handle, h', is lowered to the position shown in Fig. 1, the cams h², h³, engage the sides of jaws, D, D', and lock the jaws together. K, represents a wedge seated in slots, d⁴, in the jaws, D, D', and locked in place by a head, k, pinned thereto to prevent injury to the end of the wedge. The opposite end of the wedge is too broad to pass through the slot, d⁴, thus preventing detachment of the wedge, K, except by removing head, k.

In practice I preferably employ railway ties, or other timbers, L, L', resting across the rails and against the outside wheels of the respective trucks. The clamps, four in number are then adjusted to the rails outside the timbers, L, L', and pressed close up to said timbers. Then the handles, h', are lowered, locking jaws, D, D', together and the wedges, K, driven to position between the upper edge of the slots d⁴, and the top of the rails, which, by reason of the engaging faces of the free ends, d', d'', of the jaws being slightly diagonal, inclines the jaws backwardly, as shown in Fig. 1, bringing the serrated faces of shoes, G, into contact

with the top of the rail. Wedges, N, are preferably employed between the clamps and the timbers, L, L', to take up any lost motion or slack due to compression of the timbers. These wedges are held in place upon the forward face of the jaws, D, D', by means of ears, n. With dry rails, or under ordinary circumstances, the serrated shoes, G, are unnecessary, but where the track is 10 wet and slimy, the serrated shoes in combination with the clamping mechanism effectually prevents any slipping of the clamps. The handle, h', serves to shift the cams, h², h³, and also as a convenient means 15 for transporting and adjusting the clamps to position.

In the modification, Fig. 7, I have shown the forward portion of the clamping jaws, D², adapted to engage directly with the periphery of the car wheels without the intervention of any timbers, but preferably employ the timbers, as shown in Fig. 1.

The mechanism herein illustrated and described is capable of considerable modification, without departing from the principle 25 of my invention.

Having described my invention, what I claim is:

1. In a mechanism of the character indicated, a pair of jaws hinged together at one end and adapted to open at the opposite end to receive a rail, means for closing said jaws, and a wedge seated in slots in said jaws and adapted to engage the top of the rail.

35 2. In a mechanism of the character indicated, a pair of jaws hinged together at one end and adapted to open at the opposite end to receive a rail, rearwardly projecting brackets carried by said jaws and adapted 40 to engage the top face of said rail, means to lock said jaws in the closed position, and a wedge seated in slots in said jaws and adapted to engage the top of the rail.

3. In a mechanism of the character indicated, a pair of jaws hinged together at one end and adapted to open at the opposite end to receive a rail, rearwardly projecting brackets carried by said jaws, detachable serrated shoes carried by said brackets and 50 adapted to engage the top face of said rail, means to lock said jaws in the closed position, and a wedge seated in slots in said jaws and adapted to engage the top of the rail.

4. In a mechanism of the character indicated, a pair of jaws hinged together at one end and adapted to open at the opposite end to receive a rail, ears carried by said jaws, a lever pivotally attached to said ears and provided with cams adapted to swing into and

out of the path of said jaws in opening to 60 alternately permit said jaws to open, and to lock said jaws together upon the rail.

5. In a mechanism of the character indicated, a pair of jaws hinged together at one end and adapted to open at the opposite end 65 to receive a rail, a lever pivotally attached to ears carried by said jaws, said lever having cams to engage and lock said jaws together upon said rail, and a wedge seated in slots in said jaws and adapted to engage the top of 70 said rail.

6. In a mechanism of the character indicated, a pair of jaws adapted to grasp the opposite sides of a rail, ears carried by said jaws, and of less width than the jaws, a pivot 75 pin passing through said ears, a lever pivotally attached to said ears by said pin, and provided at one end with a handle, and at the opposite end with cams to engage and lock said jaws together upon the rail, and 80 capable of swinging out of the path of said jaws in opening.

7. In a mechanism of the character indicated, a pair of jaws adapted to grasp the opposite sides of a rail, a lever pivotally attached to said jaws and provided at one end with a handle and at the opposite end with cams to lock said jaws together upon the rail, brackets projecting rearwardly from said jaws and armed with detachable serrated 90 shoes to engage the top of the rail, and a wedge seated in slots in said jaws and adapted to engage the top of the rail.

8. In a mechanism of the character indicated, a pair of jaws adapted to grasp the 95 opposite sides of a rail head, means to lock said jaws in the closed position, brackets projecting rearwardly from said jaws and armed with detachable serrated shoes to engage the top of the rail, and a wedge engaging between the forward portion of said jaws and the top of the rail to force said shoes in contact with the rail.

9. In a mechanism of the character indicated, a pair of jaws adapted to grasp the 105 opposite sides of a rail, means to lock said jaws in the closed position, a wedge seated in slots in said jaws and adapted to engage the top of the rail, and a slack wedge adapted to 110 gravitate along the forward face of said jaws.

In testimony whereof I have affixed my signature in presence of two witnesses.

HARRY STIBBS.
